UNITED STATES PATENT OFFICE.

CHARLES D. ROSECRANS, OF HONOLULU, TERRITORY OF HAWAII.

VALVE-GRINDER CUP.

1,334,797.

Specification of Letters Patent. Patented Mar. 23, 1920.

Application filed April 5, 1919. Serial No. 287,686.

To all whom it may concern:

Be it known that I, CHARLES D. ROSECRANS, a citizen of the United States, and a resident of Honolulu, county of Honolulu, 5 and Territory of Hawaii, have invented a new and Improved Valve-Grinder Cup, of which the following is a full, clear, and exact description.

My invention relates to valve grinder 10 cups; that is, to devices used for holding the valves of internal combustion engines in order to grind the same, the holding device having to some extent the function of a vacuum cup.

More particularly stated, my invention 15 comprehends means for rendering the valve cup more particularly air tight and for facilitating the removal and replacement of the cup; my invention further contemplates a number of improvements in the mechanism 20 contained within the cup and used for the purpose of adapting the vacuum cup to valves of different types.

My invention further contemplates a number 25 of changes in the details of construction of the mechanism of the cup for the purpose of improving the general efficiency thereof.

Reference is made to the accompanying 30 drawings forming a part of the specification in which like reference characters indicate like parts throughout the several figures.

Figure 1 is a substantially central vertical section through my improved valve grinder cup.

Fig. 2 is an inverted plan or bottom view 35 of the same.

Fig. 3 is a section on the line 3—3 of Fig. 1, looking in the direction of the arrows.

Fig. 4 is a fragmentary section on the 40 line 4—4 of Fig. 1, looking in the direction of the arrows, but showing certain movable parts as occupying positions different from those that they occupy in said Fig. 1.

A revoluble stem is shown at 4 and forms 45 a part of the usual valve grinding mechanism. This stem supports a gimbal 6, which carries a plug 6^a having a threaded portion 6^b. A sleeve is shown at 5 and is provided with a portion 5^a threaded internally to fit 50 the threaded portion 6^b of the plug and also threaded externally. A cap 6^c is threaded internally to fit the adjacent portion of the sleeve 5. This sleeve carries at its low end 55 a flange 7 having a general annular form and integral with it. A hollow member 8 having generally the form of a cup and

made of rubber is provided at its lower edge with a bearing surface 8^a having a substantially annular form and adapted for engagement with the valve to be ground. 60 The rubber cup is provided with a cylindrical passage 9 and with an annular shoulder 10, the flange 7 abutting normally against this annular shoulder. The space within the cup is shown at 11. The sleeve 5 is provided 65 with a shoulder 12. Located within the sleeve 5 is a coiled spring 13, always under tension. The upper end of this spring engages the lower end of the plug 6^c. Below the spring is a plunger 14, which extends 70 down into the space 11 and carries a pair of spline keys 15 of a form which may be understood more particularly from Fig. 3, the sleeve 5 being formed accordingly, so that the plunger 14 turns with the sleeve 75 5 when the latter is rotated. Located upon the upper end of the plunger 14 is a disk 16, secured in position by threaded bolt 17, as may be understood from Fig. 1. The lower end of the plunger 14 is provided with 80 a head member 14^a, and carries a cross bar 18, this cross bar being provided with downwardly turned end portions 19. The cross bar is provided with slots 20, and extending through these slots are bolts 21. These bolts 85 support two nuts 22 and 23. Extending through these nuts are screws 24 and 25, having journal necks 26 and 27, which extend through the adjacent end portions 19 of the cross bar 18. The milled head 24^a 90 is secured rigidly to the screws 24 and 25, and is used for turning the same. The screw 24 has a right-handed pitch and the screw 25 has a left-handed pitch. The result is that when the milled head 24^a is 95 turned in one direction the two nuts 23 and 22 are driven farther apart, whereas if the milled head 24^a be turned in the opposite direction the two nuts are drawn toward each other. A driving bit 28 is provided 100 with a pair of annular bearings 28^a which encircle the screws 24, which are provided with journaled necks 25^a, for fitting the annular bearings 28^a. Thus the driving bit 28 is journaled to swing or rock. The driving bit 28 has the form of a screw-driver, and has two normally fixed positions indicated respectively in Fig. 1, and Fig. 4, as hereinafter described. A pair of anchor rods 29 and 30 are carried by the two nuts 110 22, 23. These anchor rods are mounted upon pivots 31, 32, and are each provided

with a square heel 33 and engaged by a spring 34. The anchor rods 29, 30 can be swung upon their respective pivots somewhat after the manner that the blade of a 5 jack-knife may be swung upon the handle thereof. Thus, the two anchor rods 29, 30 each have two normal positions indicated by full lines in Figs. 1 and 4. The driving bit 28 is provided with a pair of holes 35 10 and is engaged by a leaf spring 36, the latter being connected by a fastening 37 with the cross bar 18, as shown more particularly in Fig. 4. If the driving bit 28 is out of engagement with the anchor rods 29, 30, the 15 spring 36 causes the driving bit to swing up into a horizontal position, as indicated in Fig. 4. If, however, the anchor rods 29, 30 are inserted in the holes 35 of the driving bit, as indicated in Fig. 1, the driving bit 20 is held with its edge portion downward and is in appearance somewhat like a screw-driver. With the parts in this condition the anchor rods 29, 30 are virtually housed and rendered idle for all purposes, except 25 that of holding the driving bit 28 rigidly in position.

Most of the valves of the type here contemplated are of two kinds, the one being provided with holes into which the anchor rods 29, 30 may be thrust, and the other being provided with a slot into which the driving bit 28 may be fitted. My device is adapted for use with either of the two kinds of valve, the only difference being the manner 35 in which the connection is made between my device and the valve.

The operation of my device is as follows:

The parts being assembled and arranged as shown in Fig. 1, the mechanism is ready 40 for use. In order to connect it with a valve having a slot into which the driving bit 28 may be fitted, the valve is simply brought against the under side of the device shown in Fig. 1 so that the driving bit 28 is inserted within the slot. This being done, 45 pressure is applied to the valve so as to expel a portion of the air and render the rubber cup air tight. The valve, of course, clings tightly to the rubber cup. If in doing this 50 the pressure against the driving bit 28 is sufficient to overcome the pressure of the spring 13, this spring simply yields and the plunger 14 moves slightly upward. Thus, 55 the mechanism is readily accommodated to the valve.

Suppose now, that we wish to grind a valve not having the slot above mentioned into which the driving bit 28 is adapted to fit, but having instead a pair of round holes 60 in which the anchor rods 29, 30 are to be thrust. The operator turns the milled head 24^a, if need be, so as to free the anchor rods 29, 30 from the driving bit 28. This done, 65 the leaf spring 36, swings the driving bit 28 into the position indicated in Fig. 4. The

operator with his finger next grasps each of the anchor rods 29, 30, and swings it downwardly in much the same manner as he would grasp the blade of a jack-knife and pull it open. This done, the anchor rods 70 29, 30 extend straight downward and have considerable rigidity because of the pressure of the springs 34. The operator turns the milled head 24^a still farther, if need be, until he gets the nuts 22, 23 just the right 75 distance apart for the anchor rods 29, 30 to fit into the holes in the valve. This done, and the valve being pushed up tight against the rubber cup, is held in position substantially as above described. 80

Suppose now, that with the anchor rods 29, 30 extending straight downwardly, as indicated by dotted lines in Fig. 1, the valve is put on but in such a manner that the anchor rods 29, 30 do not extend into the 85 holes in the valve. As soon as the grinding mechanism is in motion the rotation of the rubber cup and parts carried thereby soon causes the anchor rods 29, 30 to turn angularly to the extent necessary to enable them 90 to enter the holes in the valve. In other words, if at any time the cup happens to be set on the head of the valve with the anchor rods 29, 30 crosswise of the holes in the valve, the cup will cling on the head of the 95 valve and the anchor rods 29, 30 will find the holes into which they will fit. This done, the vacuum cup will be unable to slip any farther.

It will be noted that spring 12 renders the 100 parts in great measure self-adjustable. Also, that the fitting of the cap 6^c upon the upper portion of the rubber member 8 goes far toward insuring an air-tight fit. It will be noted that the flange 7 being pulled against 105 the shoulder 8 also tends to render the device still further air-tight. If a little oil is put on the valve or in the cup it greatly increases the lifting or pulling power of the cup, for the purpose of holding the valve. 110

The driving bit 28 and the anchor rods 29, 30 may, if desired, be used independently of the rubber cup 8. For such valves as are easily ground and are not likely to cause trouble, this does very well. Thus used, 115 the device can be employed with almost any sort of valve. In other words, it is not necessary in all instances to employ the rubber cup 8, though in general, it is advisable to do so. I also use the driving bit and 120 anchor.

It will be noted that the nuts 22, 23 in traveling longitudinally of the screws 24, 25 are guided by the bolts 21, and these bolts slide freely within the slots 20 into which 125 they fit neatly. Thus, the nuts 22, 23 and consequently the anchor rods 29, 30, are held with considerable firmness at all times, and are not easily misplaced while the valve is in position. 130

I do not limit myself to the precise mechanism shown, as variations may be made therefrom without departing from the spirit of my invention as defined in my claims.

5 Having thus described my invention, what I claim as new and desire to secure by Letters Patent is as follows:

1. In a valve grinder, the combination of a vacuum cup provided with a cylindrical 10 passage and a shoulder partly bound in said passage, a sleeve extending through said passage and provided with a flange engaging said shoulder, and means for clamping a portion of said vacuum cup against said 15 flange, and mechanism located within said vacuum cup for engaging the valve to be ground.

2. A device of the character described, comprising a vacuum cup, a sleeve carrying 20 said vacuum cup and provided with a compartment, a spring located within said compartment, a plunger extending from said compartment through said sleeve and into said vacuum cup, a spring located within 25 said sleeve and pressing upon said plunger, and mechanism carried by said plunger for engaging the valve to be ground.

3. A device of the character described, comprising a vacuum cup, a plunger located 30 within said vacuum cup and located relatively thereto, spring mechanism for pressing said plunger in a particular direction relative to said vacuum cup, and mechanism mounted upon said plunger for engaging 35 the valve to be ground.

4. A device of the character described, comprising a vacuum cup, a sleeve extending thereinto, a plunger splined within said sleeve and extending into said vacuum cup,

spring mechanism for tensioning said 40 plunger, and mechanism mounted upon said plunger and coacting with said vacuum cup for engaging and holding the valve to be ground.

5. A device of the character described, 45 comprising a vacuum cup, mechanism mounted within said vacuum cup and coacting therewith for engaging the valve to be ground and spring mechanism connected with said last mentioned mechanism and 50 with said cup for allowing last mentioned mechanism to yield readily to said cup.

6. A device of the character described, comprising a revoluble member, a cross bar carried thereby and revoluble therewith, a 55 driving bit supported by said cross bar and adapted to fit into a slot with which the valve to be ground is provided, a pair of anchor rods supported by said cross bar, and means for connecting said anchor rods 60 with said driving bit for the purpose of holding said driving bit in a normal working position.

7. A device of the character described, comprising a vacuum cup, a supported member 65 mounted therein, a driving bit carried by said supported member, a plurality of anchor rods carried by said supported member, and means controllable at the will of the operator for fixing said driving bit in a predetermined operative position while rendering said anchor rods idle, and for fixing said anchor rods in predetermined operative positions while rendering said driving bit idle. 70
